CALCULATING MACHINE

Edward C. Walter, Orange, N. J., assignor to Monroe Calculating Machine Company, Orange, N. J., a corporation of Delaware

Application May 28, 1940, Serial No. 337,702

2 Claims. (Cl. 235—138)

The invention relates to calculating machines, and particularly to tens carry mechanism therefore, an object of the invention being to provide for the use of the same rotary carry unit in machines such as the Monroe having ten banks and those having thirteen banks of denominational keys.

The invention consists in the novel construction and combinations of parts as hereinafter set forth in the claims.

In the accompanying drawing,

Figure 1 is a vertical sectional view, taken through the carry mechanism and associated parts, shown in normal position of rest, parts being broken away.

Figure 2 is a section on the line 2—2, Figure 1.

Figure 3 is a diagrammatic view, showing the opposed series of primary and secondary carry elements, the restoring means for the settable devices related thereto and the differential actuators.

In this drawing, the invention is shown as applied to a Monroe machine, such for instance as disclosed in the U. S. patent to Britten, No. 1,474,230, dated November 13, 1923, wherein the progressively offset carry teeth or elements are arranged in two opposed spiral series, each series being continued beyond a carry element common to both series, this arrangement being also shown in the disclosure of the U. S. patent to Baldwin, No. 706,375, dated August 5, 1902. The U. S. patents to Walter, Nos. 2,089,820 and 2,147,359 are referred to for structural features.

In the drawing, the numeral 1 designates a numeral wheel, of which a series is provided, mounted on shaft 2, and having each fast thereto a pinion 3, meshing with an intermediate gear 4, which gear is operable by the related differential actuator 22 and the tens carry mechanism. Each wheel 3 is provided with a circumferential lateral projection 5, lying in the plane of a tooth 6 of a settable device 7 pivoted upon a supporting shaft 8 and provided with a spring 9 adapted to hold said device in either of two set positions, that is to say with the tooth 6 in the path of projection 5 of a numeral wheel, or upon displacement of device 7 by projection 5 of the wheel to hold an oppositely beveled surface or lug 12 of said device in depressed position. There is provided a settable device 7 for each active numeral wheel 50

6 of the machine. Upon the drive shaft 13 is provided a rotary carry unit having mounted for rotation therewith a series of circumferentially channeled sleeves 14, each provided with two spaced radial

notches in which are located two pivotal carry elements 15, one of said elements being adjustable to transmit the carry to the next higher order numeral wheel in additive operations and the other in subtractive operations, during rotation of said unit. The additive and subtractive carry elements are angularly offset from one another to form the aforesaid opposed spiral series in the well known manner.

10 Each pair of carry elements 15 is secured to the related sleeve 14 by a segmental clip spring 16 seated in a channel of the sleeve and in notches of the element. An annular helical spring 17 is seated in a second channel of the sleeve and engages the pair of carry elements to hold them normally inactive. The carry elements 15 have each a pivot intermediate of the length thereof, (being the aforesaid spring 16) and opposite arms 18 and 19 extending the one into the plane 15 of the related settable device 7 and the other into the plane of the related gear 4, and as each carry element is moved during rotation of said unit past the beveled lug or surface 12 of the related settable device 7 set in depressed position, one arm of said element will be depressed by said beveled or cam surface and the other arm will be raised into engagement between the teeth of the intermediate gear 4 related to the next higher order numeral wheel. Said element is held in such engaging position and will impart one step of movement to said higher order wheel, after which said element passing beyond said cam surface 12 will be retracted by its spring 17.

Certain of said sleeves 14 are provided each 35 with a double beveled restoring tooth and certain others of said sleeves are provided each with two double beveled restoring teeth 20 adapted for engagement respectively with a pin 21 of the related settable device 7 during rotation of said 40 unit to cam said device into normal raised position.

It will be noted by reference to Figure 3 of the drawing, that the restoring teeth 20 for the settable devices 7 related to the carry elements 15 forming the converging portions of the opposed spirals and located opposite the right hand portion of the keyboard of the machine are disposed in a single line between said carry elements; whereas the restoring teeth 20 for the devices 7 related to the carry elements 15 forming the diverging portions of the opposed spirals and located opposite the left hand portion of the keyboard are disposed in two lines on the outer sides of said carry elements, the reason for this being that the restoring teeth must act, in either direc-

tion of rotation of said unit, after the carry has been effected in the higher order wheel; that is to say the restoring teeth for said devices must follow the carry elements 15 during rotation thereof with said unit.

In a machine having ten banks of denominational keys, the carry elements 15 of the converging spirals are relied upon to transmit the carry from the lower to the higher order numeral wheels according to values set in said banks of denominational keys, and the restoring teeth 20 for the related settable devices 1 will always follow the carry elements during rotation therewith with said unit and the carry will be properly effected.

In a machine having thirteen banks of denominational keys however, if the carry element 15 common to the converging and diverging portions of the opposed spirals and the next two adjacent elements of the diverging portions of said spirals were relied upon to transmit the carry from the lower to the higher order numeral wheels according to values set in the last three banks of keys to the left of the keyboard, the carry would not be effected, because the restoring teeth 20 for the settable devices 1 related to said common element and next two adjacent elements would not follow but would precede said carry elements during rotation of said unit in either direction, and a settable device 1 depressed by the projection of a lower order wheel would be restored to normal raised position by the related tooth 20 before actuation of the related carry element and of the higher order wheel.

In order to correct this, there are provided, upon the outer sides of the diverging portions of the opposed spirals of carry elements 15, two opposed secondary series of three carry elements 15' each, located circumferentially opposite said common element and next two adjacent elements of the diverging portions of said spirals and also mounted for rotation with said unit. Said secondary series of three carry elements 15' each are progressively offset from one another to form with said common element 15 and next two adjacent elements two short converging series. Between each of these two short converging series the restoring teeth 20 for the settable devices 1 related to said common element and next two adjacent elements are arranged in a single line and will respectively follow either member of either short converging series during movement thereof with said unit in either direction.

Upon the occurrence of a tens carry following the setting of a value in any one of the last three banks of denominational keys to the left of a thirteen key bank machine and the condition of the numeral wheels 13 calling for transmission of the carry through the fourteenth carry element 15 to the left in either of the diverging portions of the opposed spirals, it is necessary to provide a special restoring tooth 20" to restore the settable member 1 related to either of said fourteenth carry elements before the other fourteenth carry element comes into active position. The said fourteenth carry elements to the left are those carry elements of the diverging portions of said spirals located next to the left beyond the secondary series of carry elements. The restoring tooth 20" is located between these fourteenth carry elements and is also mounted for rotation with the rotary carry unit.

In the use of the same rotary carry unit for

both ten key bank and thirteen key bank machines, the carry elements 15' of the secondary series are omitted in radial notches provided in the related sleeves 14 of a ten key bank machine, 5 and are installed in said notches for a thirteen key bank machine.

I claim:

1. A calculating machine, having differential actuators, numeral wheels, intermediate gears related to said wheels and to said actuators, and tens carrying mechanism including devices individually settable by the related lower order numeral wheel, and a rotary unit having mounted for rotation therewith two opposed primary spiral series of elements, each series being continued beyond an element common to both series to form converging and diverging spiral portions and the elements of one or the other series according to the direction of rotation of said unit being respectively engageable with the related settable device and thereby adjustable to engage the gear related to the higher order numeral wheel, and restoring means for said settable devices; in combination with other differential actuators located 15 opposite said common element and adjacent elements of the diverging portions of said spirals, and intermediate gears and settable devices related thereto, said rotary unit having mounted for rotation therewith two opposed secondary series of elements, each series being located circumferentially opposite said common element and adjacent elements and forming therewith two short converging series, the restoring means for the settable devices related to said common element 20 and adjacent elements being located between each of said two short converging series and serving also to restore the settable devices related to the members of said secondary series.

2. A calculating machine, having differential actuators, numeral wheels, intermediate gears related to said wheels and to said actuators, and tens carry mechanism including devices individually settable by the related lower order numeral wheel, and a rotary unit having mounted 40 for rotation therewith two opposed primary series of elements, each spiral series being continued beyond an element common to both series to form converging and diverging spiral portions and the elements of one or the other series according to the direction of rotation of said unit being respectively engageable with the related settable device and thereby adjustable to engage the gear related to the higher order numeral wheel, and restoring means for said settable devices; in combination with other differential actuators located opposite said common element and adjacent elements of the diverging portions of said spirals, and intermediate gears and settable devices related thereto, said rotary 45 unit having mounted for rotation therewith two opposed secondary series of elements, each series being located circumferentially opposite said common element and adjacent elements and forming therewith two short converging series, and special restoring means for the settable devices related to those elements of said diverging spirals located next to the left beyond said secondary series, the restoring means for the settable devices related to said common element and adjacent elements being located between each of said two short converging series and serving also to restore the settable devices related to the members of said secondary series.

EDWARD C. WALTER.
